CLAIM

The ornamental design for a level and angle finder tool, as shown and described.

DESCRIPTION

FIG. 1 is a top, front, right side perspective view;
 FIG. 2 is a front elevation view;
 FIG. 3 is a rear elevation view;
 FIG. 4 is a left side elevation view;
 FIG. 5 is a right side elevation view;
 FIG. 6 is a top plan view;
 FIG. 7 is a bottom plan view thereof;
 FIG. 8 is a top front, right side perspective view in an alternate position; and,
 FIG. 9 is a bottom front, left side perspective view in an alternate position.
 The broken line portion of the figure drawings is included to show unclaimed subject matter only and forms no part of the claimed design.

1 Claim, 5 Drawing Sheets(56)
